UNITED STATES PATENT OFFICE

167,729

HOLDER FOR PLAYING CARDS

Abraham Werner, Sr., Honolulu,
Territory of Hawaii

Application April 11, 1952, Serial No. 19,284

Term of patent 7 years

(Cl. D34—13)

To all whom it may concern:

Be it known that I, Abraham Werner, Sr., a citizen of the United States, residing at Honolulu, Territory of Hawaii, have invented a new, original, and ornamental Design for a Holder for Playing Cards, of which the following is a specification, reference being had to the accompanying drawings, forming a part hereof.

I claim:

The ornamental design for a holder for playing cards, as shown.

ABRAHAM WERNER, SR.
